UNITED STATES PATENT OFFICE.

CHARLES L. HOPKINS, OF RIVER FOREST, AND CHESTER E. WARNER, OF BERWYN, ILLINOIS, ASSIGNEES TO BENJAMIN ELECTRIC MANUFACTURING COMPANY, OF CHICAGO, ILLINOIS, A CORPORATION OF ILLINOIS.

ATTACHMENT PLUG.

Application filed January 12, 1922. Serial No. 528,647.

To all whom it may concern:

Be it known that we, CHARLES L. HOPKINS, a citizen of the United States, residing at River Forest, in the county of Cook and State of Illinois, and CHESTER E. WARNER, a citizen of the United States, residing at Berwyn, in the county of Cook and State of Illinois, have invented certain new and useful Improvements in Attachment Plugs, of which the following is a full, clear, concise, and exact description, reference being had to the accompanying drawings, forming a part of this specification.

Our invention relates to attachment plugs.

One of the objects of our invention is to provide improved means for facilitating the insertion and removal of the plug with respect to the socket.

A further object of our invention is to provide improvements in the construction of attachment plugs.

A further object of our invention is to provide a swivel shell attachment plug with improved means for facilitating its use.

A further object of our invention is to provide a separable swivel shell attachment plug with improved means for facilitating its use.

A further object of our invention is to provide a separable swivel shell attachment plug with means for screwing the swivel shell into the socket, which extend downwardly alongside the cap of the plug to enable it to be readily grasped.

Further objects will appear from the detailed description to follow and from the appended claims.

In the drawings in which two embodiments of our invention are shown—

Figure 1 is a side elevation of a separable swivel shell attachment plug embodying our invention;

Fig. 2 is a view from the right of Fig. 1, the body part being shown in section;

Fig. 3 is a bottom plan view of the body part of a plug;

Fig. 4 is a plan view of a fibre disc forming part of the construction;

Fig. 5 is a perspective view showing a contact and conductor member;

Fig. 6 is a side elevation of a swivel shell attachment plug embodying our invention; and

Fig. 7 is a bottom plan view of Fig. 6.

Referring now to the drawings in detail, and first to Figs. 1 to 5 inclusive, the construction shown therein comprises a separable swivel shell attachment plug 10, having an extension handle 11 pivotally connected at 12 to the threaded shell contact to facilitate screwing the plug into a socket.

By reason of the fact that the handle 11 is pivotally mounted with respect to the plug, it will yield when necessary to permit the necessary movement of the cord 13 without exerting undue side pull on the plug, the position to which the handle 11 may be swung being indicated in dotted lines in Fig. 1.

This handle 11 is in the form of a wire loop or bail pivotally mounted at 12 on the ears 14, which may be formed integral with the metal ring or ferrule 15 secured to the threaded shell contact 16. In order to insulate the handle 11 from the threaded shell contact 15, an insulating ring 17 is provided, the inner edge of which is held in a channel formed in the lower part of the threaded shell contact 16, and to the outer end of which is secured the sheet-metal ferrule 15. This ring may be a stamping of fibre or any other suitable material. A short fibre sleeve 18 is provided to prevent accidental contact with the threaded shell contact 16 when the latter is screwed into the socket.

The cap 19 may be the ordinary attachment plug cap, provided with contact blades 20 for engagement with the contact members 21 and 22 respectively, mounted on the insulating base 23 of the body part of the plug, and electrically connected with the shell contact 16 and center contact member 24 respectively. The contact member 22 may be a sheet metal stamping secured on the insulating base 23 by means of the center contact 24 which may be in the form of a tubular eyelet having its lower portion embedded in the insulating base, and its upper portion extending through and flanged over the stamping forming the contact member 22.

The contact members 21 may be formed as part of a sheet metal stamping, having a yoke-shaped portion 25, and a pair of sliding contact members 26, which slidably engage an inwardly extending flange on the threaded shell contact 16, (Figs. 2, 3 and 5). The stamping may be provided with a pair of upwardly turned lugs 27 which extend

into correspondingly located recesses in the insulating base 23 to position the stamping with respect to the base. The insulating base 23 is suitably recessed to receive the contact members 21 and 22, and to permit the entry of the contact blades 20 of the cap 19.

In order to hold the threaded shell contact in place, a circular insulating disc 28 is provided (Figs. 2 and 4) which is secured to the lower face of the insulating base 23 by means of an eyelet 29 embedded in the insulating base 23 and extending through a central opening 30 in the disc 28 and flanged over underneath the disc. This insulating disc 28 is provided with a pair of openings 31 for the passage of the contact blades 20. It is also provided with a pair of positioning openings 32 to receive 20 positioning lugs 33 (Fig. 3).

In use, the extension handle 11 facilitates the insertion of the plug into a socket, particularly when the socket is at a considerable height, making it difficult to reach 25 with the ordinary plug, or if the socket is in a deep shade which would make it hard to reach up into the shade with the ordinary plug.

Because of the hinging of the handle, 30 it can readily be swung to one side if the cord is pulled sidewise against the handle. As the handle does not confine the cord in any way, as would be the case if it were a rigid tubular handle containing the cord, 35 it does not cause any undue strain to be exerted on the plug when the cord is pulled sidewise.

In Figs. 6 and 7 we have shown our invention as applied to an ordinary swivel 40 shell plug 35, the extension handle 36 being connected to the swivel threaded shell 37 by means of a universal joint connection at 38. In this construction, the wire handle 36 is pivoted at 39 to a ring 40, which in turn is pivotally connected at 41 to a pair of ears bent downwardly from the ferrule or ring 42 secured to the threaded shell 37.

In order to insulate the handle 36 and the threaded shell contact 37, an insulating 50 ring may be provided similar to the ring 17 in the construction previously described, the inner edge of this insulating ring being secured to the threaded shell contact 37, the ring 42 being secured to the outer edge 55 of this insulating ring.

For convenience in manipulation, the lower end of the handle 36 may be formed 60 into a coil 43, through which the cord 44 extends. This coil 43 serves as a sort of thumbpiece in screwing the threaded shell contact into the socket. The universal joint connection permits the handle 43 to swing with the cord 44 no matter in what direction the cord leads from the plug, and the 65 handle 36 exerts no confining influence on

the cord itself, so that no undue strain is exerted on the plug when the cord is pulled to one side.

Having thus described our invention, what we claim as new and desire to secure by Letters Patent of the United States is:

1. An attachment plug comprising a threaded shell contact, and an extension handle having a universal joint connection with said plug.

2. An attachment plug comprising a threaded shell contact, and an extension handle having a universal joint connection with said threaded shell contact.

3. An attachment plug comprising a body portion, a threaded shell contact swiveled with respect to said body portion, and an extension handle having a universal joint connection with respect to said swivel shell.

4. An attachment plug comprising a threaded shell contact, and an extension handle having a universal joint connection with respect to said threaded shell contact, said universal joint connection comprising a ring coaxial with said threaded shell contact and pivotally mounted with respect thereto, and a loop handle pivotally connected with said pivot ring.

5. An attachment plug comprising a body portion, a threaded shell contact swiveled with respect to said body portion, and an extension handle having a universal joint connection with respect to said swivel shell, said universal joint connection comprising a ring coaxial with said threaded shell and pivotally mounted with respect thereto, and a loop-shape handle pivotally mounted on said ring.

6. A swivel shell plug comprising an insulating base, a threaded shell contact surrounding and swiveled with respect to said insulating base, an insulating ring secured to said threaded shell contact, a ferrule secured to said insulating ring, and an extension handle pivotally secured to said ferrule.

7. An attachment plug comprising a threaded shell contact and an extension handle pivotally secured to said plug, said extension handle comprising a wire extending alongside the cord, and having a loop embracing the cord.

8. A separable swivel shell plug comprising an insulating base, a center contact mounted thereon, a threaded shell contact surrounding said base and swiveled with respect thereto, blade-engaging contacts mounted thereon, and a cap having blades for engaging said blade-engaging contacts, one of said blade-engaging contacts being formed as part of a sheet metal stamping, said sheet metal stamping comprising a sliding contact portion and a spring contact tongue.

9. A separable swivel shell plug comprising an insulating base, a center contact

mounted thereon, a threaded shell contact surrounding said base and swiveled with respect thereto, blade-engaging contacts mounted thereon, and a cap having blades for engaging said blade-engaging contacts, one of said blade-engaging contacts being formed as part of a sheet metal stamping, said stamping comprising an arch-shaped portion, a spring contact portion extending from the top of the arch and sliding contact members at the feet of the arch.

10. An attachment plug comprising a base having a center contact, recesses in the sides of said base, a blade-engaging contact electrically connected to said center contact and extending into one of said recesses, an insulating plate secured to the lower end of said base and provided with openings arranged to register with the recesses in said base, a shell contact rotatably mounted between said base and said insulating plate, a second blade-engaging contact mounted between said base and said shell contact and extending into one of said recesses.

15. 11. A swivel attachment plug comprising a base, a center contact mounted on said base, a blade-engaging contact electrically connected to said center contact, an insulating plate secured to the lower end of said base and having openings therethrough arranged to receive the blades of an attachment plug cap, a shell contact rotatably mounted between said base and said insulating plate, and a second blade-engaging contact mounted between said base and said shell contact and arranged to frictionally engage said shell contact.

20. 12. A separable swivel shell plug comprising an insulating base, a center contact

mounted thereon, a threaded shell contact surrounding said base and swiveled with respect thereto, blade-engaging contacts arranged to extend into openings in said base and in electrical contact with said plug contacts, and an insulating member on one end of said base, said threaded shell being held in place by said insulating member, and a loop-shaped handle secured to and insulated from said threaded shell.

13. A separable swivel shell plug comprising an insulating base, a center contact mounted thereon, a threaded shell contact surrounding said base and swiveled with respect thereto, blade-engaging contacts arranged to extend into openings in said base and in electrical contact with said plug contacts, and an insulating member on one end of said base, said threaded shell being held in place by said insulating member, and a loop-shaped pivoted handle secured to and insulated from said threaded shell.

14. A separable attachment plug comprising a body portion and a cap portion, said body portion comprising center and side contacts and blade-engaging contacts, said cap portion comprising blades for engaging said blade-engaging contacts, and an extension handle permanently mounted on said plug to move about an axis transverse to the axis of the plug, said extension handle comprising a bail-shaped member having one arm pivoted on one side of the plug and the other arm pivoted on the other side of the plug.

In witness whereof, we have hereunto subscribed our names.

CHARLES L. HOPKINS.
CHESTER E. WARNER.
